Primary Examiner — Rosemary K Tarcza(74) *Attorney, Agent, or Firm* — Lee & Hayes, PLLC(57) **CLAIM**

The ornamental design for a multi-source micro USB charger, as shown and described.

DESCRIPTION

FIG. 1 is a perspective view of a multi-source micro USB charger, taken from the top, right and back;

FIG. 2 is a top plan view of the multi-source micro USB charger of FIG. 1;

FIG. 3 is a bottom plan view of the multi-source micro USB charger of FIG. 1;

FIG. 4 is a front elevation view of the multi-source micro USB charger of FIG. 1;

FIG. 5 is a back elevation view of the multi-source micro USB charger of FIG. 1;

FIG. 6 is a left side elevation view of the multi-source micro USB charger of FIG. 1; and,

FIG. 7 is a right side elevation view of the multi-source micro USB charger of FIG. 1.

The broken lines are directed to environment and are for illustrative purposes only. The broken lines form no part of the claimed design.
